UNITED STATES PATENT OFFICE.

JAMES C. DOWEJKO, OF BROOKLYN, NEW YORK, ASSIGNOR TO NATIONAL SEAL COMPANY, INC., OF BROOKLYN, NEW YORK, A CORPORATION OF NEW YORK.

CLOSURE.

Application filed December 21, 1927. Serial No. 241,502.

My invention relates to closures used for sealing the openings in containers, jars or bottles in which the closure is adapted to be repeatedly applied to and removed from the container, and furthermore to tightly seal the container when the closure is affixed and locked in sealing position, even after repeated applications and removals.

The objects of my invention are, among other things, to provide an improved closure structure of this type of container and closure whereby a more perfect seal and reseal is secured for such improved closure; to provide a closure with a depending skirt portion and a plurality of inwardly extending lips to engage with radially projecting lugs on the container in which the leading edges of the lip portions shall be formed to engage with progressively increasing pressure the under surfaces of the lugs to draw down the closure upon the rim of the container openings. Furthermore I also provide a novel and reinforced stop end for each of the lips to coact with the lugs to limit the rotation of the closure in the seating direction which stop end at the same time tends to draw down the cap of the closure upon the rim of the container opening with a distributed, substantially uniform pressure, thereby furnishing an effective closure seal which can be repeatedly used for resealing the container opening after the closure has been initially removed.

A further feature is to reinforce each stop end by inwardly indenting its rear portion to form a more or less curved rib or brace which shall prevent any undue rotation of the closure beyond its predetermined closed position thereby rendering more effective the coaction between the stop ends and bottle lugs.

With the above and other objects in view, my invention comprises the novel construction, combination and arrangement of parts hereinafter described and then particularly pointed out in the appended claims.

In the accompanying drawings, Fig. 1 is a perspective view of the improved upturned closure showing my invention;

Fig. 2 is a bottom plan view of the closure, the top of the container or bottle with its lugs being shown in dotted lines;

Fig. 3 is a section taken on the lines 3—3 of Fig. 1; and

Fig. 4 is an enlarged perspective view

showing the details of the reinforced stop end.

Similar numerals refer to similar parts throughout the several figures.

Referring to the drawings, the closure 5 proper is formed preferably of a resilient sheet-metal, and comprises the circular top or cap 6 from which depends the annular skirt portion 7 which is usually knurled. The skirt 7 has a series of spaced-apart inwardly turned lips 8 segmental in shape and somewhat longer than the therewith coacting lugs 9 formed on the neck 10 of the bottle as shown in Fig. 2. The leading end 11 of each lip 8 is cut square and is adapted to initially engage the rounded ends of the lugs 9 when the closure 5 is preliminarily rotated toward the Fig. 2 locking position.

The stop ends of the lips 8 are formed by bending the following ends of the lips 8 inwardly to form the therewith right-angled faces 12 and curved braces 13 integral with the skirt 7 and lips 8, which braces 13 reinforce with a local rigidity the adjacent parts so that the stop faces 12 will not yield in any direction when they come into coacting engagement with the lugs 9 as the closure 5 is rotated and brought to the locked position shown in Fig. 2. Such braces 13 are preferably crimped by firstlapping the following ends of the lips 8 against the skirt 7 and then the instruck indentations 14 are punched from the outside into the overlapped or folded-over double thickness of sheet-metal whereby such curved crimped braces 13 have imparted to them an exceptional rigidity to support the stop ends and faces 12 when the lugs 9 are pressed against the latter in rotating and locking the closure to the bottle.

The operation of my improved closure is substantially as follows: The closure 5 is set on the top of the bottle neck 10 so that the lugs 9 are disposed between the several lips 8, the top or cap 6 resting on the rim of the neck 10. Then the closure 5 is horizontally rotated or twisted so that the leading ends 11 of the lips 8 engage the leading ends of the lugs 9. The continued rotation of the closure or cap causes the lips 8 to ride along the under surfaces of the lugs 9 until the faces 12 engage the leading ends of the lugs 9 which stops the closure rotation. The curved double-thickness of the braces 13 prevents the faces 12 from yielding against any continued

rotation, and also prevents any local spreading of the skirt 7 which might allow the faces 12 to slip by their lugs 9 and so unseal the bottle. The effect of these curved crimped braces 13 is to produce a compound rigidity for the following lip ends and integral faces 12 as well as for the adjacent skirt portion so that the closure 5 is effectually prevented from further rotation. It is manifest that I have embodied in my improved closure certain structural features which add to the effectiveness of the seal under all conditions of use no matter what may be the size of the closure and irrespective of the thickness and resiliency of the sheet-metal used in its construction.

I claim as my invention:—

1. In combination with a container having a lug, a closure having an inturned lip to engage said lug upon rotation of the closure in one direction, and a stop end to engage the lug formed with lug-engaging face and a curved brace in transverse alinement with the face.
2. In combination with a container having a lug, a closure having an inturned lip to engage said lug upon rotation of the closure in one direction, and a stop end to engage the lug formed with lug-engaging face and a curved brace of double thickness integral with the face and lip and in transverse alinement with the face.
3. In combination with a container having a lug, a closure having an inturned lip to engage said lug upon rotation of the closure in one direction, and a stop end to engage the lug formed with lug-engaging face and a curved brace comprising an instruck indenta-

tion of double thickness crimped in the following end of the lip in transverse alinement with the face.

4. In combination with a container having a lug, a closure having an annular depending skirt and an inturned lip integral with the skirt to engage said lug upon rotation in one direction, and a stop end to lock with said lug, said stop end comprising a flat face and an integral supporting curved brace of double thickness formed from the folded-over end of said lip and skirt.

5. In combination with a container having a lug, a closure having an annular depending skirt and an inturned lip integral with the skirt to engage said lug upon rotation in one direction, and a stop end to lock with said lug, said stop end comprising a flat face and an integral supporting curved brace of double thickness formed from the folded-over inwardly indented end of said lip and skirt.

6. In combination with a container having a lug, a closure having a lip to engage said lug upon rotation of the closure in one direction, said lip having a stop end to limit the rotation of the closure, and a supporting brace for said stop end comprising a crimped folded portion of the lip behind said stop end and integral therewith.

7. In combination with a container having a lug, a closure having a lip to engage said lug upon rotation of the closure in one direction, said lip having a stop end to limit the rotation of the closure, and a supporting brace for said stop end comprising a crimped inwardly indented folded portion of the lip behind said stop end and integral therewith.

JAMES C. DOWEIKO.
